P. A. JACKSON

AUTOGRAPHIC REGISTER

Filed Aug. 11, 1924

INVENTOR
PHILIP A. JACKSON,

By Paulmin Paulmin,
ATTORNEYS

UNITED STATES PATENT OFFICE.

PHILIP A. JACKSON, OF DAYTON, OHIO, ASSIGNOR TO THE EGRY REGISTER COMPANY, OF DAYTON, OHIO, A CORPORATION OF OHIO.

AUTOGRAPHIC REGISTER.

Application filed August 11, 1924. Serial No. 731,336.

My invention relates to autographic registers and in particular to a means of winding a record strip.

It is the object of my invention to provide means of winding a record strip so that the record strip will be maintained in alignment with the remaining sheets and will not have the actuating apertures which engage with the pins of a pin wheel torn or mutilated.

It has been found heretofore that one of the common faults of a record strip actuated by a pin wheel is that such a strip has its holes torn due to the pulling of the record roll on the strip advancing the strip faster than the pin wheel will enable it to advance, or vice versa.

I have found that by directing the paper strip around a substantial portion of the periphery of the pin wheels against the pin wheel drums so that the paper is also in engagement with a substantial proportion of all of the teeth of the pin wheel and that as I then convey the record strip over a plurality of stationary guides or bars which are in frictional engagement with the paper prior to its being wound on the record roll I am enabled to maintain the paper of the record strip in engagement with the pin wheels so firmly and positively that no slippage takes place which would result in the tearing of the holes in the paper.

It is my object to so actuate the paper and wind it that there is no slipping on the actuating element. Thus the paper being firmly held against the actuating element is not subject to the shifting or pulling by the record roll which results in the mutilation of the paper when my invention is not employed.

It is a further object of my invention to provide a ready means of adjusting and connecting the record strip with the record roll so that the friction devices may be readily placed in position without the necessity of complicated adjustments which are difficult for the ordinary user to make. By my arrangement all that is necessary is to connect the record strip to the record roll and then insert the carrying plate which supports the friction member bringing the paper to its proper degree of tautness.

It is a further object to so arrange the record sheet that it is engaged by more pins on

the pin wheels than are the sheets which are issued out of the register. It is my object to secure perfect and automatic alignment of all of the forms on all of the sheets so that it is possible to print and number the record sheet to correspond with the sheets issued out of the register.

It is a further object to so construct the machine that when taking the record roll from the register it is possible to sever the record sheet at the same point that other bills on the sheets are torn off which enables the operator to take from the register the last record made which is a desirable feature.

Referring to the drawings:

Figure 1 is a section through the register taken vertically adjacent one wall of the register illustrating the arrangement of parts.

Figure 2 is a detail plan view of the record roll at one end together with the disk clutch.

Figure 3 is a perspective of the plate which carries one of the friction members.

Figure 4 is a detail showing the arrangement of the gearing and its adjustment and the method of driving the pin wheels.

Referring to the drawings in detail:

1 is the base of a register, 2 is the rear end, 3 is the forward end which is pivoted at 4 to the side walls 5. The upper forward end of the side walls is provided with a sliding cover 6 which has a lug 7 engaging with the upper and inner face of the forward wall 3 so that the locking of the forward wall to the side walls maintains this sliding cover in position. The rear end of the sliding cover is turned upwardly as at 8 in order to provide a supporting and ejection surface for the sheets 9 and 10 which are being ejected.

These sheets, together with the record roll sheet 11 are supplied from rolls on the axles 12, 13 and 14. The sheets pass over the guide rolls 15, 16 and 17 in the usual manner and thence over the writing table 18 which is cut away with slots 19 to receive the pins 20 of the pin wheels 21.

The forward end of the writing table is so arranged that it overhangs the center of the pin wheels and has an upper tapered surface 22 over which the record roll strip passes downwardly and directly over the

forward face of the pin wheel in close engagement with about 30% of the periphery of each pin wheel, which in itself prevents considerable shifting of the record roll strip 5 and consequent tearing of the strip. It will be understood, of course, that while approximately a 30% engagement is shown in the drawing, this may be varied to a greater or lesser extent as conditions may warrant, and 10 I do not desire to be limited to any particular amount of engagement.

The record roll strip then passes backwardly as at 23 beneath and to the rear of the center of the pin wheels where it passes 15 over a bar or edge or axle which is substantially rounded such as 24. The sheet is in frictional engagement with this stationary edge. The sheet then passes forwardly as at 25 over the stationary bar 26 and downwardly as at 27 over the stationary bar 28 and thence rearwardly at 29 to the bottom of the record roll 30. This record roll is supported on an axle 31. This axle is provided with a pair of plates 32 and 33. Adjacent 25 each plate is a friction disk 34 and 35 embracing between it the record roll driving gear 36. This gear 36 is driven by a train of gears 37, 38 and 39, 39^a secured to gear 39 and the gear 40 which is carried on the 30 axle 41 supporting the pin wheels.

Thus the resistance of the paper to the movement of the roll 30 is compensated for by this slipping clutch shown in Figure 2.

The friction bar 24 is carried on a sliding plate 42 which is supported in guides 42^a. The friction plate occupies a diagonal position and is prevented from sliding too far inwardly by a depending lug 43 on either side of its forward edge, each of which lugs 40 engage with the corresponding lug 44 on the inner wall on either side of the register.

The pin wheels are driven by the usual handle operated shaft 45 working through a gear 46 to a gear 47 which in turn drives 45 the pin wheel gear 40. The gear 47 is carried on a swinging plate 48 which is carried by the axle 41 adjacent one of the side walls of the register and provided with a slot 50. The plate 48 being swung on the axle 41 50 may have a range of adjustment equal to the length of the aperture 50. A pin 49 carried by the register wall holds the plate 48 in the desired adjusted position. By mounting the gear 47 on this adjustable plate 48, 55 I am enabled to change the size of the gears to accommodate the machine to different lengths of forms. These gears are prevented from rearward movement by a pawl 51 carried on the inside of one of the register walls.

A cover 52 is pivoted at 53 which has a writing opening 54. The forward end of this cover has a cut-off edge 55 and is cut away as at 56 to receive the pin wheels.

65 It will be understood that I do not desire

to be limited to various details of construction but comprehend within my invention such modifications as may be necessary to adapt it to varying uses and varying conditions.

It is apparent that any form of frictional member will be useful in securing the requisite friction on the record roll strip, but a rotating member such as a roller will not be satisfactory as it does not provide the 70 resistance to the pull of the record roll. The frictional member must resist the movement of the paper by the record roll sufficiently to prevent the tearing of the paper on the pins on the pin wheels or other actuating 75 mechanism used to actuate the sheets. A freely moving member such as a roller will not provide this resistance and therefore 80 will not be satisfactory.

Having thus fully described my invention, 85 what I claim as new and desire to secure by Letters Patent of the United States is:

1. In an autographic register having a plurality of strips, pin wheels adapted to engage with said strips in perforations therein, one of said strips being a record roll strip and arranged to be in engagement with a substantial portion of the peripheries of the pin wheels and a plurality of friction members over which said record strip is passed 90 and then wound on a record roll, a record roll and means to permit said record roll to slip relatively to the pin wheels, and means to carry one of said friction members so that it can be supported in position in the register or moved out of position out of the register, and means in the side walls of the register to maintain said last mentioned means in position.

2. In an autographic register having a 105 plurality of strips, one of which is a record roll strip, pin wheels to feed the strips, a record roll for receiving the record roll strip and a slideable plate having one edge adapted to be moved into said register against said record strip to frictionally engage therewith at a point intermediate the pin wheels and the record roll, and means cooperating 110 with said slideable plate so that a loop is formed in the record strip to insure the 115 maximum engagement of the strip with the frictional edge of the plate.

3. In an autographic register having a plurality of strips, one of which is a record roll strip, pin wheels to feed the strips, a 120 record roll for receiving the record roll strip and a slideable plate having one edge adapted to be moved into said register against said record strip to frictionally engage therewith at a point intermediate the pin wheels and the record roll, and means cooperating with said slideable member so that a loop is formed in the record strip to insure the maximum 125 engagement of the strip with the frictional edge of the support, said strip being kept 130

in engagement with the drums of the pin wheels approximately 30% of their peripheries.

4. In an autographic register having a plurality of strips, one of which is a record roll strip, pin wheels to feed the strips, a record roll for receiving the record roll strip and a slidable plate having one edge adapted to be moved into said register against said record strip to frictionally engage therewith at a point intermediate the pin wheels and the record roll, and means cooperating with said slidable member so that a loop is formed in the record strip to insure the maximum engagement of the strip with the frictional edge of the support, said strip being kept in engagement with the drums of the pin wheels approximately 30% of their peripheries, the frictional edge of the sliding support being beneath the pin wheels and to the rear of their centers.

5. In an autographic register having a plurality of strips, one of which is a record roll strip, pin wheels to feed the strips, a record roll for receiving the record roll strip and a slidable member having one edge adapted to be moved into said register against said record strip to frictionally engage therewith, said slidable member having its frictional engaging edge so formed as to insure the maximum engagement of the strip with the frictional edge of the slidable member, said strip being kept in engagement with the drums of the pin wheels approximately 30% of their peripheries, the frictional edge of the slidable member being beneath the pin wheels and to the rear of their centers, and a second frictional support beneath the slidable member and closely adjacent thereto so arranged that the center of the record roll is below and between the points of frictional engagement with the record strip, and a third frictional member below the second for engaging with the strip.

6. In an autographic register having a plurality of strips, one of which is a record roll strip, pin wheels to feed the strips, a record roll for receiving the record roll strip and a slidable member having one edge adapted to be moved into said register against said record strip to frictionally engage therewith, said slidable member having its frictional engaging edge so formed as to insure the maximum engagement of the strip with the frictional edge of the slidable member, said strip being kept in engagement with the drums of the pin wheels approximately 30% of their peripheries, the frictional edge of the slidable member being beneath the pin wheels and to the rear of their centers, and a second frictional support beneath the slidable member and closely adjacent thereto so arranged that the center of the record roll is below and between the points of frictional engagement with the record strip, and a third frictional member below the second for engaging with the strip.

7. In combination in a pin wheel register having a plurality of strips, one of said strips adapted to be passed around a substantial portion of the pin wheels in close engagement therewith, a frictional member carried on a slide located below and to the rear of the center of the pin wheels, a second frictional member located closely adjacent to the slide near the front of the machine, forward of the pin wheels and beneath the slide, and a record roll located below the slide and the frictional members, means to drive the pin wheels and record roll synchronously, and a friction clutch interposed between said driving means and said record roll to permit the record roll to slip with respect to the pin wheels.

In testimony whereof, I affix my signature.

PHILIP A. JACKSON.
